DESIGN FOR A DUMP WAGON BODY

George D. Alexander, Minneapolis, Minn.

Application September 30, 1939, Serial No. 87,451

Term of patent 14 years

To all whom it may concern:

Be it known that I, George D. Alexander, a citizen of the United States, residing at Minneapolis, in the county of Hennepin and State of Minnesota, have invented a new, original, and ornamental Design for a Dump Wagon Body, of which the following is a specification, reference being had to the accompanying drawing, forming part thereof.

Referring to the drawing:

Fig. 1 is a perspective view as the dump wagon body would appear from the side and front portions, while Fig. 2 is a perspective view from the other side and the rear thereof.

I claim:

The ornamental design for a dump wagon body, as shown.

GEORGE D. ALEXANDER.
